UNITED STATES PATENT OFFICE.

JAMES I. AYER, OF CAMBRIDGE, MASSACHUSETTS, ASSIGNOR TO SIMPLEX ELECTRIC HEATING COMPANY, OF CAMBRIDGE, MASSACHUSETTS, A CORPORATION OF MASSACHUSETTS.

DESIGN FOR AN ELECTRIC RANGE.

44,719.

Specification for Design.

Patented Oct. 14, 1913.

Application filed August 14, 1913. Serial No. 784,789. Term of patent 14 years.

To all whom it may concern:

Be it known that I, JAMES I. AYER, a citizen of the United States, residing at Cambridge, in the county of Middlesex and State of Massachusetts, have invented a new, original, and ornamental Design for an Electric Range, of which the following is a specification, reference being had to the accompanying drawings, forming part hereof.

Figure 1 is a front view in perspective of the range, showing the plurality of cooking heaters carried on top of the stove portion, together with the switch panel and roasting and warming ovens; Fig. 2 is a rear view in perspective, showing the plurality

of cooking heaters on the stove portion and the bus wires of the stove, and the backs of the roasting and warming ovens; Fig. 3 is an end view in perspective of the stove portion, looking from the left, viewing Fig. 1; and Fig. 4 is an end view in perspective, looking from the right, viewing Fig. 1, showing the oven.

I claim:

The ornamental design for an electric range as shown.

JAMES I. AYER.
